Technical drawing of a mechanical assembly, labeled Fig. 5. The drawing shows a top-down view of a base structure with various components labeled with numbers:

- 21: A rectangular block on the left side.
- 22: A vertical cylindrical component on the right side.
- 23: A horizontal slot or track in the center.
- 24: A small rectangular block on the left side.
- 25: A horizontal slot or track on the right side.
- 26: A vertical cylindrical component on the far left.
- 27: A vertical cylindrical component on the far right.
- 28: A vertical cylindrical component on the right side.
- 29: A horizontal slot or track in the center.
- 30: A vertical cylindrical component at the bottom center.

The drawing illustrates the relative positions and orientations of these components within a mechanical system.

UNITED STATES PATENT OFFICE

WILLIAM F. CLARK, OF BALTIMORE, MARYLAND

METHOD OF AND APPARATUS FOR OPERATING UPON PIPES AND SIMILAR TUBULAR ARTICLES

Application filed September 5, 1928. Serial No. 304,152.

This invention relates to a method and apparatus primarily adapted to perform finishing operations upon metal pipe stock, but not limited thereto, and the following description will be confined to such primary adaptation for purposes of clarity and conciseness of explanation of the construction and operation of the apparatus and the steps of the method.

According to the present practice, the pieces of pipe stock are run from the sizing machine, while still at an intense heat, onto a cooling rack, frame or stand over which they are caused to travel with a rolling motion, the cooling rack being of such a length that by the time the pipe stock has travelled from one end of the rack to the other it will have become sufficiently cool and longitudinally rigid to be handled. After the pieces of pipe are discharged from the cooling rack they are transferred, usually by hand, to a sawing or cutting machine by which their ends are sawed or cut off to make them of desired, standard length. When the ends have thus been severed the pieces of pipe are transferred, again usually by hand, to a reaming machine by which both ends are reamed to remove the burr produced by the sawing or cutting operation and to provide a smooth end finish.

It will be apparent that, when operated upon in this manner, the pieces of pipe go through a number of separate handlings requiring the time and labor of a number of men, and floor space for a number of machines, and during such handlings are apt to become bent or warped or otherwise injured and in consequence not salable.

The object of my invention is to provide a method of and means for simplifying these finishing operations whereby time, labor and floor space are conserved and a product of a higher standard of uniformity made possible.

The invention consists in a method of and apparatus for operating upon pipes and similar tubular articles whereby the operations of cutting the pieces of pipe to standard length and reaming their cut ends are automatically performed preferably during

their travel over the cooling rack, as I will proceed now to explain and finally claim.

In the accompanying drawings illustrating the invention, in the several figures of which like parts are similarly designated,

Fig. 1 is a plan view of a complete apparatus embodying my invention;

Fig. 2 is a side elevation thereof;

Fig. 3 is an enlarged fragmentary sectional elevation, taken substantially on the line 3—3 of Fig. 1 and showing the speed reducing driving gear of the operating devices;

Fig. 4 is an enlarged sectional elevation of one of the pipe transferring devices;

Fig. 5 is a fragmentary plan view of the same;

Fig. 6 is a view similar to Fig. 4 illustrating the cycle of operations of the transferring devices;

Fig. 7 is a further enlarged face view of one of the pipe clamping mechanisms;

Fig. 8 is a side view of the pipe clamping mechanism and associated parts looking at the right-hand side of Fig. 7;

Fig. 9 is a view of the opposite side of the pipe clamping mechanism;

Fig. 10 is a top plan view of the same;

Fig. 11 is a view similar to Fig. 7 but showing the clamping jaws in clamping engagement with a pipe;

Fig. 12 is a side elevation, upon an enlarged scale, of the reaming machine;

Fig. 13 is a partial central sectional side view of same;

Fig. 14 is an end view thereof looking at the left-hand end of Fig. 12, and

Fig. 15 is a transverse section taken on line 15—15 of Fig. 13, looking in the direction of the arrows.

The cooling rack, supporting frame or stand, is composed, in the embodiment shown, of a plurality of longitudinal members 1, preferably of channel section, arranged with their flat faces adjacent to each other but spaced to receive plates 2, suitably supported flat-wise by them and below the plane of their upper flanges, thus forming a plurality of uniformly spaced channeled guides in which

travel conveyor chains 3, hereinafter more fully described.

Intermediate the channeled guides are other longitudinal members 4, the upper surfaces of which lie in the same plane as the upper flanges of the members 1. All of the longitudinal members 1 and 4 are supported upon transverse beams 5, which in turn are carried by columns 6, the arrangement of 10 same being such that the longitudinal members are arranged at a slight incline (see particularly Fig. 2).

At the higher or discharge end of the cooling rack is arranged a transverse shaft 8, 15 driven by suitable speed reducing gearing 7, 7' from a main source of power, such as an electric motor 8, through a shaft 9. The shaft 8 carries a plurality of fixed sprockets 10, one aligned with each channeled guide, 20 and a similar sprocket 11 is carried at the lower or pick-up end of each of the channeled guides. The conveyor chains 3 mesh with these sprockets 10 and 11 and are advanced slidingly over the plates 2 by the driving action of the sprockets 10, in the direction of arrow a, Fig. 2.

At regular intervals throughout their 30 length the chains 3 are provided with conveyor lugs 12 (Figs. 3, 4 and 6) of such a height as to extend sufficiently above the plane of the top flanges of the members 1 and 4 to engage with the pieces of pipe resting upon the members 1 and 4.

At the discharge end of the cooling rack 35 downwardly inclined skids 13 are provided over which the pieces of pipe may be discharged into a suitable trough, bin, conveyor or the like, not shown.

The apparatus as thus far described, that 40 is the cooling rack per se, is well known in the art and operates substantially as follows:—

The pieces of pipe coming from the sizing machine, at an intense heat, are fed to the 45 cooling rack transversely thereof, one at a time, and are supported thereon at a plurality of points throughout their length by the longitudinal members 1 and 4. The lugs 12 of the several chains 3 being so arranged as 50 to align transversely of the rack, a lug of each chain will engage with and advance each piece of pipe with a rolling motion up the incline of the top flanges of the members 1 and 4. As the pieces of pipe are thus advanced in parallelism normal to the longitudinal members 1 and 4, they will gradually cool, and their rolling motion will tend to 55 keep them straight, so that when they arrive adjacent to the discharge end of the cooling rack they have cooled sufficiently and are sufficiently rigid to permit them to be manipulated for finishing purposes. When 60 the pieces of pipe reach the discharge end of the cooling rack they are discharged by the conveyor chains 3 down the skids 13 and 65 into the trough or the like hereinbefore mentioned.

The cooling rack illustrated is approximately thirty-five feet in length, and, as intimated, I have discovered that when the 70 pieces of pipe have traveled along the first twenty-three or so feet of its length they have cooled sufficiently and have become sufficiently rigid to permit of manipulation for cutting to standard length and reaming. I therefore mount within approximately the last twelve feet of length of the rack the mechanisms for automatically cutting and reaming the two ends of the plurality of pieces of pipe as they are advanced in uniform order 75 along the rack. Two sets of such mechanisms A and B are employed for operating successively upon the two ends of the pieces of pipe, and inasmuch as these sets are similar in all respects, a detailed description of one 80 will suffice for both.

It will be understood that the pieces of pipe as they come to the cooling rack are of 85 such a length as to extend beyond the sides of the rack, and it is these protruding ends that are cut off in reducing the length of the pipes to a uniform standard.

At a suitable position relatively to the 90 travel of the pieces of pipe on the cooling rack, and at a distance from the side thereof determined by the ultimate desired length of pipe, I mount a circular saw 14 as a member of the mechanisms A. This saw may be driven by a motor 15 or it may derive motion from 95 any other suitable source of power, such as a line shaft and pulleys and belt. As a piece of pipe is advanced by the flat faces 12' of the lugs 12 it is forced against the saw which cuts off its protruding end.

The next operation is the reaming of the 100 cut end of the pipe, and for this step the pipe must be released from the influence of the conveyor chains 3 and supported and held stationary while a reaming tool is forced against it, and it must thereafter be replaced 105 in the path of movement of the conveyor chains so that it may have its opposite end similarly operated upon and be subsequently discharged from the cooling rack.

Obviously, the operations of removing the 110 pipe from the conveyor chains, supporting and clamping and then reaming it, and returning it to the conveyor chains must be performed in timed relation to the travel of the chains, and this I have accomplished by 115 means of the devices next to be described.

At appropriate points transversely of the 120 cooling rack I mount a number (three being shown) of forked rests 16 (Figs. 1, 3, 4, 5 and 8) having shanks 17 splined as shown 125 at 18, Fig. 4. The splines 18 are engaged by keys or feathers, not shown, in the bearing members 19 in which the rests are supported and insure their proper alignment, and the shanks 17 are also threaded as at 130

20 for the reception of adjusting nuts 21 whereby the height of the rests may be determined. Obviously, this height must be such that when a pipe is supported by the 5 rests the lugs 12 of the carrier chains 3 may pass beneath it without touching it.

For the purpose of successively raising and removing a pipe from the conveyor 10 chains 3, placing it upon the rests 16 and then removing it from the rests, after its end has been reamed, and replacing it in the conveyor 15 chains, I provide a plurality of transfer devices preferably equal in number to and arranged adjacent to the rests. Each of these 20 transfer devices comprises a pair of cooperating carrier members 22 and 23 having forked extensions 24 adapted to travel into and out of the path of travel of the pipes in the conveyor chains 3. The extensions 24 merge into eccentric straps 25 and terminate in slotted guide members 26 which ride upon and are guided by lugs 27 fixedly supported by suitable stands 28. The eccentric straps 25 embrace complementary eccentrics 29 carried by and rotatable with a shaft 30 driven by suitable reducing gearing 31, 32, 33 (Fig. 3) from the main drive shaft 9. By an inspection of Fig. 6, it will be seen that as the eccentrics 29 rotate with shaft 30 they 35 will cause a pipe carried by the conveyor chains 3 to be picked up at the position of carrier members 22 indicated in dotted lines at 22a, moved through the upper portion of the orbit 22b and deposited in the rests 16, as shown, the carriers thereafter completing 40 the traversing of their orbits to their initial pick-up positions 22a by the time another set of lugs 12 has advanced another pipe to this position. The carrier members 23 have 45 meanwhile traversed their orbits 23b, and at the proper time pick up the pipe from the rests 16, move it through the upper part of the orbit 23b and deposit it in the conveyor chains at approximately the position indicated in dotted lines at 23a.

It will be understood that in the interval between the time when the pipe is deposited in the rests by the members 22 and the time when it is removed from the rests by the 50 members 23, it is clamped and reamed. It will be understood also that during this interval the conveyor chains have moved forward a distance not quite equal to the space between two adjacent lugs 12.

55 The pipes must be clamped while being reamed to prevent their turning with the rapidly revolving reaming tool and to prevent them from backing away from the reaming tool as it is advanced during the reaming operation. To accomplish this clamping I provide a clamping device for each of the sets of mechanism A and B. These clamping devices (see Figs. 3, 7, 8, 9, 10 and 11) have a pair of jaw members 34 and 35 adjustably mounted by screw adjust-

ing devices 36 in levers 37 and 38, respectively. These levers are pivotally mounted upon pins 39 and 40, respectively, carried by the stands 28 and are provided with extensions 41 and 42, respectively, carrying rollers which cooperate with cam surfaces on a cam mounted on and rotating with the shaft 30.

The extension 42 has a single centrally mounted roller 44 (see Fig. 8) and the extension 41 carries two spaced rollers 43 (see Fig. 9). The cam 47 has three cam surfaces, two of which, 45, are similar and arranged adjacent to its faces and act upon the two rollers 43, and the other of which, 46, is arranged between the two designated 45 and acts upon the roller 44. The rollers 43 and 44 are held in operative engagement with their cooperating cam surfaces by means of a spring 48.

The extension 42 is pivoted to the lever 38 at 49 and a heavy spring 50 is interposed between these parts, expansion of the spring being limited by means of cooperating stops 51 and 52 carried by the extension 42 and lever 38, respectively. The compression of the spring, and hence its stiffness, may be adjusted by means of an adjusting screw 53 provided with a jamb nut 54. By this arrangement, it will be seen that when the jaws 55 are forced toward each other under the influence of cam 47 to clamp a pipe, as shown in Fig. 11, the gripping action will be resilient, though adequate for its purpose, thus removing strain from the operating parts of the clamping device.

The reaming mechanism comprises a reaming tool 55 carried by a mandrel 56 mounted in slide bearings 57 (see Fig. 13) in a sleeve or spindle 58 which is rotatably carried in bearings 59 in stands 60. Rotation is imparted to the mandrel 56 by means of a toothed clutch member 61 which slidably engages its complement in the hub of a gear 62 driven by a pinion 63 on the shaft 64 of a motor 65 or other power imparting means. Rotation of the mandrel 56 is imparted to sleeve 58 by means of a pin 66 which passes through the mandrel and through slots 67 in the sleeve and terminates in a collar 68 provided with a circumferential rib 69. This rib 69 engages a complementary groove 70 in a split housing 71 provided with trunnions 72 (Figs. 12 and 15) which are engaged by a shifter yoke 73 formed on the end of a bell-crank lever 74 pivoted at 75 (Figs. 12 and 13.)

By this arrangement it will be seen that the mandrel 56, sleeve 58, collar 68 and gear 62 rotate as a unit, the rotary motion of mandrel 56 being transmitted to the parts 58 and 68 by means of the pin 66. Sliding movement of the mandrel 56 within the sleeve 58 is caused by shifting of the housing 71, the motion of same being transmitted to the man-

15 mandrel by means of the groove 70, rib 69 and pin 66, which latter, though it must turn with the mandrel, may slide in the slots 67.

16 Mounted for rotation with the shaft 30 is a face cam 76 the follower of which is a roller 77 carried by the lever 74 and backed up by a stiff spring 78. The roller 77 is held in engagement with the cam 76 by means of an adjustable tension spring 79 connected with the end 80 of the lever 74 and with one of the stands 60.

17 Thus it will be apparent that upon rotation of shaft 30 in timed relation to the travel of the conveyor chains 3 and the operation of the transfer and clamping mechanisms, the cam 76 will so operate as to project the rotating mandrel 56 at the time when a pipe is held in the clamping mechanism upon the rests 16 and will thus force the reaming tool into cutting engagement with the end of the pipe, as shown in Fig. 13.

18 The outward thrust or travel of the mandrel 56 may be regulated by means of a plurality of adjusting screws 81 carried by the hub 82 of the cam 76 and bearing against a rotating abutment 83 clamped on the shaft 30.

19 The operation of the device may be apparent from the foregoing description, but in the interest of clearness it may be further explained as follows:—

20 Assuming that the conveyor chains 3, saws 14, transfer devices 22, 23, clamping mechanisms 34, 35 and reaming tools 55, 55 and their associated parts are all in operation, the pieces of pipe coming from the pipe-forming machine are fed at intense heat to the cooling rack at its lower or pick-up end. Here they will be supported by the longitudinal members 1 and 4 and will be engaged, in sequence, by the lugs 12 of the conveyor chains 3 and rolled along the members 1 and 4 toward the discharge end of the cooling rack.

21 Looking now at Fig. 1 from the left-hand or discharge end of the cooling rack, it will be seen that as the pieces of pipe advance toward the reader they will first be engaged by the saw at the left which will cut off their protruding left-hand ends, then they will be picked, one-by-one, from the conveyor chains by the transfer devices of the set of mechanisms A and deposited in the rests 16 where they are immediately clamped by the clamping mechanism and reamed by the reaming tool. Immediately upon completion of the reaming operation they are picked out of the rests 16 by the transfer mechanisms and replaced in the conveyor chains. 22 Next, their right-hand ends are presented to the saw 14 at the right and cut off. Then they are picked, one-by-one, from the conveyor chains by the transfer devices of the set of mechanisms B and deposited in the rests 16 of that set where they are immedi-

23 ately clamped and reamed. After being reamed they are again placed in the conveyor chains and carried thereby to the discharge end of the cooling rack from which they roll down the skids 13 into the trough, bin, or the like provided for them.

24 It will be seen that by my invention I have provided a method and means for operating upon pipes or similar tubular articles preferably while they are in the process of cooling, without the necessity for the several handlings now common and without transporting them to and from several machines. Moreover, I have so combined the mechanisms for performing the required finishing operations upon such articles as to materially economize floor space, time and labor, and to perform these operations automatically and rapidly. Furthermore, due to the fact that hand manipulation of the pipes or the like is avoided until after they have become cold and rigid, loss due to bending and warping is eliminated, and the finishing operations being automatically performed with mechanical precision a more uniform product is obtained than is possible under the present practice.

25 Various changes in, modifications of and additions to the method and apparatus are deemed to be within the spirit of the invention and the scope of the following claims.

26 What I claim is:

1. The method of producing pipes and similar tubular articles having finished ends, which comprises moving said articles over a support, cutting off the ends of said articles and reaming the cut ends at intervals in timed relation to the movement of the articles.

2. The method of producing pipes and similar tubular articles having finished ends, which comprises moving said articles over a support whereon they are permitted to cool, cutting off the ends of said articles, and reaming the cut ends at intervals in timed relation to the movement of the articles, the cutting and reaming operations being performed while the articles are cooling.

3. A method of operating upon pipes and similar tubular articles, which comprises moving said articles over a rack at a predetermined speed, cutting off the ends of said articles during their movement, arresting the movement of said articles in succession for a predetermined period of time, reaming the cut ends thereof during such period, and thereafter re-establishing the articles in movement over the rack and discharging them therefrom, the period of arrested movement being timed in relation to the speed of movement of the articles over the rack.

4. Apparatus for operating upon pipes and similar tubular articles, including a rack, means for causing said articles to travel longitudinally of said rack in an arrange-

ment transversely thereof, means for severing the ends of said articles in succession during their travel, means for arresting the movement of said articles, means for finishing the severed ends of the articles while their movement is arrested, and means for re-establishing said articles in their travel along the rack after the completion of the finishing operation, the period of arrested movement and the finishing operation performed therein being timed in relation to the movement of the travel-causing means.

5. Apparatus for operating upon pipes and similar tubular articles, including a supporting frame upon which the articles travel, means for severing the ends of said articles in succession during their travel, means for arresting the movement of said articles, means for finishing the severed ends of the articles while their movement is arrested, and means for re-establishing said articles in their travel along the supporting frame after the completion of the finishing operation.

6. Apparatus for operating upon pipes and similar tubular articles, including a rack, a conveyor arranged to travel longitudinally of said rack, means on said conveyor for imparting movement to a tubular article arranged transversely of said rack, a cutting device for severing the end of said article during its travel, a rest arranged transversely of said rack, means for transferring said article from said movement-imparting means to said rest, means for holding said article in fixed relation to said rest, means for finishing the severed end of the article while it is thus held, and means for transferring the article from the rest into engagement with the movement-imparting means; the operations of transferring to said rest, holding and finishing and transferring from the rest back to the movement-imparting means being timed in relation to the travel of the conveyor.

7. Apparatus for operating upon pipes and similar tubular articles, including a rack, a travelling conveyor provided with lugs adapted to cause a pipe arranged transversely of the rack to travel longitudinally thereof, a cutter arranged adjacent to the side of the rack and adapted to sever the protruding end of the pipe during its travel, a rest arranged transversely of the rack, a transfer device adapted to remove said pipe from the influence of said lugs and place it upon said rest, a clamping mechanism adapted to clamp said pipe in fixed relation to said rest, a reaming tool, means for operating said tool to ream the severed end of the pipe while clamped, a transfer device for removing said pipe from said rest after the completion of the reaming operation, and means for imparting functioning power to said conveyor, transfer devices, clamping mechanism and reaming mechanism in timed relation to each other.

8. Apparatus for operating upon pipes and similar tubular articles, including a rack, a travelling conveyor associated with said rack and provided with lugs adapted to cause a pipe arranged transversely of the rack to travel longitudinally thereof, a cutter arranged adjacent to one side of said rack and adapted to sever the protruding end of said pipe during its travel, means providing a rest arranged transversely of the rack, a transfer device adapted to remove said pipe from the influence of said lugs and place it upon said rest, a clamping mechanism for holding said pipe in fixed relation to said rest, a reaming tool, means for operating said tool to ream the severed end of the pipe while clamped, a transfer device for removing said pipe from said rest after completion of the reaming operation and after release of said clamping mechanism, a cutter, transfer devices, clamping mechanism and reaming mechanism arranged adjacent to the other side of said rack and adapted to operate upon the other end of the pipe in a manner similar but subsequent to the corresponding devices before mentioned, and means for imparting functioning power to said conveyor, transfer devices, clamping mechanisms and reaming mechanisms in timed relation to each other.

9. Apparatus for operating upon pipes and similar tubular articles, including a rack, a travelling conveyor associated with said rack and provided with lugs adapted to cause a pipe arranged transversely of the rack to travel longitudinally thereof, a reaming tool and mechanism for actuating same arranged in such position relatively to the rack as to operate upon the end of the pipe carried thereby, means providing a rest arranged transversely of said rack and in alignment with the axis of said reaming tool, transfer mechanism including a plurality of transfer devices adapted to engage the pipe at a number of points throughout its length and transfer it from the conveyor to the rest for reaming of its end and thereafter back to the conveyor, means for fixedly clamping the pipe during the reaming operation, and means including a source of power for imparting functioning movement to said conveyor, transfer mechanism, clamping means and reaming mechanism in timed relation to each other.

In testimony whereof, I affix my signature.

WILLIAM F. CLARK.
